UNITED STATES PATENT OFFICE.

BERRY H. COLLINS, OF SHREVEPORT, LOUISIANA.

GUIDING ATTACHMENT FOR PENHOLDERS.

No. 875,506.

Specification of Letters Patent.

Patented Dec. 31, 1907.

Application filed March 19, 1907. Serial No. 363,184.

To all whom it may concern:

Be it known that BERRY H. COLLINS, a citizen of the United States, residing at Shreveport, in the parish of Caddo and State 5 of Louisiana, has invented certain new and useful Improvements in Guiding Attachments for Penholders, of which the following is a specification.

This invention relates to a new and useful 10 improvement in educational appliances and has particular reference to a pen holder.

The invention has for its object to provide a pen holder for students.

In the art of penmanship it is of great im- 15 portance that the writing be accomplished by a wrist or muscular arm movement as contrasted to a finger movement. The finger movement comes most natural to the great majority of persons and is readily ac- 20 quired, whereas the art of using the wrist or muscular arm movement is one which must be studied and practiced. The disadvantage of the finger movement is that in comparatively long periods of writing the hand be- 25 comes cramped and tired. It is also impos- 80 sible with this movement to write a flowing hand, by virtue of which the writing is much more speedily and legibly accomplished.

My invention therefore aims to attain the 30 above object by the provision of a pen holder embodying associated means for so position- 85 ing the fingers of the writer that all move- 90 ment used in forming the letters must be made from the wrist and arm and cannot be 95 made by movement of the fingers.

My invention further aims to embody said 40 means in a simple practical, and efficient de- 95 vice and one which will be inexpensive to manufacture, and it consists in the following 45 features of construction and arrangement as will be hereinafter described, with refer- 100 ence to the accompanying drawing in which,

Figure 1, is a front perspective view illus- 50 trating the practical application of my in- 105 vention. Fig. 2, is a rear perspective view 110 showing the same. Fig. 3, is a perspective view of a pen holder constructed in accord- 115 ance with my invention. Fig. 4 is a plan view partly in section of one of the guiding 120 elements. Fig. 5, is a side elevation of the 125 same, Fig. 6, is a plan view partly in section 130 of the other guiding element, and Fig. 7, is a 135 side elevation thereof.

In the practical embodiment of my in- 140 vention I employ an elongated holder 1,

which is designed to be grasped by the hand and which carries at its lower end a clip 2, designed to receive a penpoint 3, of conventional form.

The invention specifically resides in at- 60 tachments to be carried by the holder 1, and which confines the fingers of the writer in the desired position.

The lower guiding element 4, is adapted to 65 receive thereon the fingers of the writer and comprises separate members 5 and 6, looped at one end to form clasping members 7, and provided with a loose stud 8, having a threaded end adapted to receive an adjusting thumb 70 screw 9 for tightening or loosening said clasping members 7, about the holder 1. This guiding element 4, is adapted to extend at right angles from the holder 1, when clasped there- 75 to and serves not only as a coöperative for the confinement of the finger but also as a 80 rest to steady the pen in its movements, the little finger of the hand being adapted to rest in the rear, and the remaining fingers to lie over the same, as clearly shown in Fig. 2.

The guiding element 10 is adapted to project rearwardly on a horizontal plane into the crotch of the hand and to form an inclined angle with the holder. To this end the element 10 comprises the separate members 85 11 and 12 looped at their forward ends to form clasping members 13 disposed at an incline to the members 11 and 12 adapted to be clasped about the holder 1 by means of the adjusting thumb screw 14 adapted to be re- 90 ceived upon the threaded end of the loose stud 15, projecting through the member 11, and through the member 12. The rear ends of the members 11 and 12 terminate in laterally extending heads 16, which engage within 95 the crotch of the hand.

The manner of use will be clearly understood by reference to Figs. 1 and 2 in which it will be seen that by reason of its inclined clasp the element 10 extended rearwardly on 100 a horizontal plane within and engaging the crotch of the hand. It will also be seen that the element 4 is connected adjacent the pen point 3 and receives the fingers as heretofore described. Thus each of the elements 4 and 105 11 coöperate with the other in preventing the writer bending his fingers and in necessitating the use of a free and easy swing of the wrist and forearm to accomplish the purpose in view.

110

Having thus described my invention what I claim is,

1. A pen holder comprising a rest bar having one end fixed thereto and the other end free, said rest bar extending at an angle to said holder, and a member secured to said holder above said rest bar and extending rearwardly in a horizontal plane.
2. A pen holder comprising a rest bar having one end fixed thereto and the other end free, said rest bar extending at an angle to said holder, and a member secured to said holder above said rest bar and extending rearwardly in a horizontal plane, said member coöperating with the said rest bar for the purpose described.
3. A pen holder comprising a rest bar secured thereto at an angle and having one end fixed and the other end free, and a member secured to said holder above said rest bar and extending rearwardly in a horizontal plane, said member terminating in an enlarged

head and coöperating with said rest bar for the purpose described.

4. In a device of the character described, the combination with an elongated holder of a pair of guiding bars adjustably secured thereto, for the purpose described.

5. In a device of the character described, the combination of an elongated holder and a plurality of coöperating guide-bars adapted to be clamped thereto at separate points, for the purpose described.

6. In a device of the character described, the combination with an elongated holder of two guiding elements, each consisting of two members looped at one end, and adapted to be secured to said holder.

In testimony whereof I affix my signature in presence of two witnesses.

BERRY H. COLLINS.
